UNITED STATES PATENT OFFICE.

LYMAN O. GOODWIN, OF NORTH ANDOVER, MASSACHUSETTS, ASSIGNOR TO HIMSELF AND GEORGE L. WRIGHT, OF SAME PLACE.

DESIGN FOR A CYLINDER FOR GOVERNORS.

SPECIFICATION forming part of Design No. 34,718, dated July 2, 1901.

Application filed February 7, 1901. Serial No. 46,444. Term of patent 14 years.

To all whom it may concern:

Be it known that I, LYMAN O. GOODWIN, a citizen of the United States, residing at North Andover, in the county of Essex and State of Massachusetts, have invented a certain new, useful, and original Design for a Cylinder for Governors, of which the following is a specification, reference being had therein to the accompanying drawings.

10 In the drawings, Figure 1 represents a side elevation of a cylinder for governors, illustrating my new design. Fig. 2 represents an end view of the same.

15 The leading feature of my new design for cylinders for governors consists in the design as herein shown and described.

As shown in the drawings, the upper semi-cylindrical portion 5 is connected by the plane surface 6 with the lower convex portion 7,

which is extended to the web 8 by the surface 9, the plane surface 6 having the raised annular boss 10. At the ends of the upper portion are the vertical annular flanges 11 11, and at the ends of the lower portion are the vertical annular flanges 12 12, which connect 25 with the webs 8 8 by the curves 13 13, while between the flanges 11 and 12 are the inclined surfaces 14 14, connected by the vertical surface 15.

What I claim is—

20 The design for a cylinder for governors as herein shown and described.

In testimony whereof I affix my signature in presence of two witnesses.

LYMAN O. GOODWIN.
